UNITED STATES PATENT OFFICE

ALBERT C. SCHICKLER, OF CLEVELAND, OHIO, ASSIGNOR TO EDMUND E. ALLYNE, OF CLEVELAND, OHIO

LIQUID SEAL FOR ABSORPTION SYSTEMS

Application filed September 8, 1927. Serial No. 218,280.

This invention relates to refrigerating apparatus and more particularly to absorption systems and means for maintaining the proper head or column of refrigerant in the evaporator.

In absorption refrigerating systems great difficulty is encountered in maintaining the proper column of refrigerant in the evaporator under all conditions and especially in the face of the ever present tendency for the ammonia gas, for example, during the boiling period, to carry over with it some of the absorbing agent, which collects in the evaporator, reduces its efficiency and ultimately blocks the entire system. Various suck backs and other devices for draining the undesirable absorbing agent back to the boiler at different stages of the process have been provided but they have not been fool proof and do not function consistently throughout a long period of repeated refrigerating and heating cycles. The present invention has overcome these difficulties by providing a suck back trap preferably located close to and in communication with the bottom of the evaporator and connected by its drain to the same pipe or conduit which conveys the expanded gas back to the boiler from the evaporator. This arrangement seems to produce such a balancing of pressures within the evaporator and trap and indeed, within this portion of the circuit, such that the proper column of refrigerant is maintained in the evaporator and undesirable collection of absorbing agent in this part of the apparatus is avoided.

Other features of the invention will be brought out more fully in the following description, drawings and claims.

Referring to the drawings, Fig. 1 is a schematic illustration of a refrigerating system including the present invention and Fig. 2 is a sectional view of the suck back trap. While the invention, in its broadest scope, is applicable to many different kinds of refrigerating systems or apparatus, it has been shown for purposes of illustration in connection with an intermittent cyclic absorption system, including a suitable still 1 adapted to receive a charge of aqua ammonia, for example, to a level substantially that indi-

cated at A in Fig. 1. This still is provided with a reentrant well 2 in its side. Connected near the bottom and at its ends is a suitable cooling loop comprising the vertical leg 3, a sediment trap 4, an upturned vertical portion 5, and a more horizontal portion 6 leading to an inlet connection 7 entering the opposite end of the boiler. This loop is provided with heat radiating fins 8.

Connected to the top of the boiler is a gas outlet pipe 9 extending through a suitable cooling jacket 10 supplied with cooling water by the circulating pipes 11 and 12. This forms a rectifier for relieving the gas of some of its entrained absorbing agent, which the rectifier collects and drains back into the boiler. The opposite end of the pipe 9 is connected to a riser loop 13 extending to a considerable height and connecting to a return gas pipe 14. The former of these two pipes is of relatively large diameter to furnish additional rectifying means. The lower end of the pipe 14 extends down to a point near the bottom of a trap well 15 adapted to contain a quantity of mercury or other heavy sealing liquid. The side of the trap near its top is connected to a pipe 16 leading to the top of a condenser coil 17. The condenser coil and a portion of the loop, including a part of the leg 3, the sediment trap 4, the portion 5 and portion 6 are all enclosed in a tank 18 adapted to be supplied with cooling water by means of the pipes 19 and 20.

The trap 15 is also connected to a pipe 21 diametrically opposed to pipe 16 and rising to substantially the same height as the pipe 13 and then returning in a downwardly extending pipe 22 to the lower part of the more vertical loop portion 5 inside of the tank 18.

The bottom of the condenser communicates with a pipe 23 which leads up to the evaporator storage tank 24 located in a heat insulating casing 24a of the refrigerator or box. This liquid ammonia storage tank is provided with an outlet pipe 25 connected to the top of an ice freezing coil 26 arranged in a heat insulated freezing compartment 27 closed by a suitable insulated front door 28. The outlet pipe 25 is also connected to the top of a cooling chamber coil 29 located in a flue or bay 30

preferably forming a part of the casing for the entire evaporator. This flue is provided with an upper opening 31 adapted to be more or less closed by a shutter 32 operated by a suitable handle 33 at the front. By manipulating this shutter air circulation through the flue may be controlled at the top. The lower part of the flue communicates through an opening 34 with the main cooling chamber 10 of the box.

The lower ends of both coils 26 and 29 are connected to a common sump or header 35, which communicates by a vertical pipe 36 directly with the bottom of the supply tank 15. This pipe 36 may be provided with a heat insulating jacket 37 for decreasing evaporation therein and providing a means for directly delivering the liquid ammonia from the heat insulated tank 24 to the header 35 and to the bottoms of the coils 26 and 29 and allowing evaporation and boiling in these two coils with discharge of gas through the pipe 23.

The header 35 is connected to a downward-25 ly extending pipe 38a which leads to the bottom of a suck back trap casing comprising the lower sump 38 and an enlarged upper portion 39. A pipe 23a extends in through the side of the casing 39 just above the center 30 and extends to and is in communication with the vertical leg of the pipe 23, as shown. The sump 38 of this trap is provided with a bath of mercury 40 sufficient in quantity to balance in the pipe 38a and the entire evaporator the 35 desired column or charge of liquefied ammonia. Any excess or any additional absorbing agent which comes over during heating or distillation will pass this trap and flow back through the pipe 23 to the condenser, from 40 which it is forced over into the trap 15 and thence into the cooling loop and back to the boiler. This arrangement of the suck back trap in a closed circuit with the upper part of the pipe 23 and the evaporator produces 45 very effective operation of the suck back and does not result in unbalanced pressures which might interfere with the proper maintenance of the desired column of liquefied ammonia in the evaporator.

50 The boiler may be provided with a gas burner 41 having a mixer 42 and a supply line 43 having a valve 70.

In operation during the heating period the 55 gas is driven over from the boiler through the rectifier to the trap 15, thence to the top of the condenser 17. Here the gas collects in liquefied form and is ultimately forced up to the evaporator storage tank 24 through the pipe 23. At the storage tank it passes down 60 into the two coils, if they are empty, and into the suck back trap. Here the mercury column is sufficient to maintain the predetermined desired head or column of liquid ammonia but any excess or any heavier absorbing 65 agent will pass the trap and flow down

through the pipe 23 and ultimately find its way back into the bottom of the boiler through the loop. By having the suck back trap connected to the gas return pipe from the evaporator all the pressures in and about the 70 circuit formed between the evaporator and suck back trap will be balanced so that no undue effect is produced upon the trap. This advantageous result follows even more particularly when the absorption system is arranged to have the gas flow to, and return from, the evaporator through one pipe or line, as in the disclosure in Fig. 1.

By having the suck back trap itself consisting of a lower sump for the sealing liquid and an enlarged elongated upper portion with the evaporator pipe extending to substantially the bottom of the sump and the drain back pipe from the trap extending to substantially the center of the enlarged portion, the 85 apparatus is protected against the drainage of the sealing liquid to other parts of the system when the apparatus is tilted or moved in different positions as in shipment, because the sealing liquid can always find ample room 90 in the trap without any danger of it passing out through either of the pipes entering the trap.

What I claim is:

1. Refrigerating apparatus of the intermittent absorption type, comprising an evaporator, a condenser, still-absorber means, means for conducting condensed refrigerant to the evaporator, and trap means connected to drain by gravity from the bottom of the evaporator to said conducting means and containing a heavy sealing liquid, the entire trap means from its connection to the evaporator to its connection to the conducting means lying below the evaporator, thereby 100 maintaining a predetermined column of desirable refrigerant within the evaporator and draining weak liquor from the evaporator to said conducting means.

2. Refrigerating apparatus of the type described in claim 1, wherein the trap means comprises a casing for containing said heavy sealing liquid, a pipe leading from the bottom of the evaporator to a point below the surface of the sealing liquid in said casing, and another pipe leading from the space above said sealing liquid to said refrigerant conducting means.

3. Refrigerating apparatus of the intermittent absorption type, comprising an evaporator, a condenser, still-absorber means, a single pipe for supplying condenser refrigerant to and for returning expanded refrigerant from the evaporator to the still-absorber means, and trap means connected to drain by gravity from the bottom of the evaporator to said pipe and containing a heavy sealing liquid, the entire trap means from its connection to the evaporator to its connection to said pipe lying below the 120

evaporator, thereby maintaining a predetermined column of desirable refrigerant within the evaporator and draining weak liquor from the evaporator to said pipe.

- 5 4. Refrigerating apparatus of the type described in claim 3, wherein the trap means comprises a casing including a lower sump for the heavy sealing liquid and a larger upper portion for receiving said sealing liquid
10 when the trap is tilted, a pipe leading from the bottom of the evaporator to a low point in the sump below the level of sealing liquid therein, and another pipe entering the larger upper portion of the casing and extending
15 to substantially the center thereof and connected to the gas return pipe from the evaporator to the still-absorber means.

In testimony whereof I hereby affix my signature.
